CIRCUIT CONTROLLER

James F. Beal, Renfrew, Ontario, Canada, assignor to The Bryant Electric Company, Bridgeport, Conn., a corporation of Connecticut

Application April 6, 1943, Serial No. 481,985

27 Claims. (Cl. 200—5)

1

This invention relates in general to electric circuit controllers, and more specifically to return means for multi-position switches.

In multi-position switches such as the switch shown in Charles H. Hodgkins, Patent No. 2,331,191, issued October 5, 1943, and assigned to the same assignee as this application, wherein a rotary switch operating handle is movable 360° in either direction and is provided with a plurality of operative positions and an "off" position, a great deal of effort may be required in adjusting the switch, since it may be necessary to rotate the switch a full 180°. The effort required is multiplied when a plurality of such switches are provided, such as on an electric range for the control of each heating unit thereof. Particularly in electric range applications, it has been found that these switches are often left at an "on" position, or if a hasty attempt is made to turn them to "off" position, that they often are not completely turned to "off" position. This results in a personal hazard, causes waste of electrical power, and may cause burning and consequent waste of food.

Accordingly, one object of this invention is to provide a switch of the type described with an automatic means to effect return of the switch to its "off" position.

Another object of this invention is to provide for a switch which is movable in opposite directions from an "off" position to a plurality of operative positions, novel means for automatically returning the switch to its "off" position after adjustment to an operative position in either direction.

Another object of this invention is to provide for a switch which is rotatable 360° in either direction from an "off" position to a plurality of operative positions, novel means for resetting the switch to its "off" position by the same manual operation irrespective of the direction or the number of degrees of rotation of the switch.

One difficulty in providing spring reset means for switches having a plurality of operative positions, is that these switches generally employ some sort of spring indexing means to define each position of the switch, and if a resetting spring is employed which is strong enough to overcome the indexing means the force required to manually adjust the switch becomes excessive.

Therefore, another object of this invention is to provide in spring reset means for a switch of the type described, means for releasing the switch indexing means upon resetting so that the reset spring need not be of excessive strength.

Another object of this invention is to provide a novel spring arrangement for indexing a multi-position switch which also biases the contacts of the switch into engagement.

These and other objects of this invention will

2

become more apparent upon consideration of the following description of a preferred embodiment thereof when taken in connection with the attached drawings, in which:

Fig. 1 is a central sectional view through a switch embodying this invention.

Fig. 2 is an exploded perspective view of the reset mechanism shown in Fig. 1.

Fig. 3 is a section taken substantially on the line III—III of Fig. 1.

Fig. 4 is a view similar to Fig. 3 but showing the position of the parts after rotation of the switch handle substantially 300°.

Fig. 5 is a view also similar to Fig. 3, but illustrates still another position of the reset mechanism.

Fig. 6 is a side elevation view of the reset mechanism shown in Figs. 1 to 5 with a portion of the switch casing cover shown in section.

Fig. 7 is a front view of the switch shown in Fig. 1.

Fig. 8 is a plan view showing the interior of the switch casing with the cover and actuating cam removed, and

Fig. 9 is a view similar to Figs. 3 to 5 but illustrating still another position of the reset mechanism.

Referring to the drawings, the novel switch reset mechanism is illustrated in connection with a switch 2 similar to the switch shown in the above-mentioned patent of C. H. Hodgkins. The switch shown on the drawings, like the Hodgkins switch, is provided with an open sided casing 4 of insulating material, preferably a molded insulating material. The open side of casing 4 is provided with a cover plate 6 which may be removably secured in position by screws 44. The switch casing is also provided with a plurality of terminals 8, and mounted on the bottom wall of the casing are a plurality of annularly arranged spaced contact segments 10. There may be two concentric rings of contact segments 10, with the space between the segments of each ring occupied by segments 11 of insulating material.

Actuating cam member 12 is rotatably mounted by actuating shaft 16 within the casing. As shown, the actuating shaft is provided with a square section 17 adapted to be received in a similarly shaped opening in actuating cam 12. The actuating cam carries a bridging contact 18 embedded in the undersurface thereof for bridging the two rings and connecting opposite contact segments 10. Actuating cam 12 may also have

peripheral cam surfaces for actuating resilient switch arms such as 14, positioned at one or more sides of the casing as in the Hodgkins switch. Each switch arm 14 has a portion adapted to move into and out of engagement with a stationary contact 15, and the switch arms, contacts and

contact segments are electrically connected with appropriate terminals 8. For a more complete description of the construction and operation of a switch of this type, reference is hereby made to the above-mentioned patent of C. H. Hodgkins.

This switch differs from the Hodgkins switch in that cover 6 is provided about the aperture through which actuating shaft 16 extends, with a plurality of annularly spaced indented portions 20. The portions 20 are for the purpose of receiving balls 22 supported by a ball supporting member 26 extending transversely of the actuating shaft. The actuating shaft 16 is provided with a longitudinally extending slot 24 which may be formed by a saw-cut or the like, and ball support 26 extends through this slot, and is located in a diametrically extending slot 25 provided in the outer surface of actuating cam 12. The actuating cam is also provided with pockets aligned with balls 22 for receiving coil compression springs 28 engaged between the bottom of these pockets and ball support 26 to bias the support and balls 22 towards cover 6, and at the same time urge actuating cam 12 toward the bottom wall of casing 4 to bias bridging contact 18 into engagement with the contact segments mounted on the bottom wall of the casing.

An actuating handle 30 is provided with an aperture therethrough, preferably D-shaped in section to receive the similarly shaped outer end of actuating shaft 16 so as to be capable of rotating the shaft upon rotation of handle 30. A release bar 32 is formed integral with ball support 26 and extends from an intermediate portion of the latter, longitudinally through slot 24 in actuating shaft 16 and beyond the outer end thereof. The outer end of release bar 32 is preferably reduced in width, as shown at 34, for rotatably receiving a push button 36 having a sleeve adapted to work in counterbore 38 provided in the outer end of actuating handle 30. Push button 36 may be retained on release bar 34 by a split ring 35 adapted to be received in a groove in push button 36.

From the structure thus far described, it will be apparent that rotation of actuating handle 30 will cause rotation of actuating shaft 16 and cam 12, to cause bridging contact 18 to successively bridge the various pairs of contact segments 10, and cause actuation of cam operated switch members 14. Indentations 20 in cover 6 are located so that balls 22 will enter diametrically opposed indentations at each closed circuit position of the switch as well as at the "off" position, shown in Fig. 1. As shown in Fig. 7, this switch has six positions equally spaced about the actuating shaft, so that six indentations 20 are provided correspondingly spaced about the actuating shaft. This positively indexes the switch so that in moving from one position to the other, it is necessary that the balls 22 be rolled out of indentations 20 against the bias of springs 28. This requires greater force in initiating movement from a switch position than is required in moving between switch positions. Moreover, as soon as an operative position or the "off" position of the switch is approached, springs 28 will assist the operator in moving the switch, because balls 22 will roll into the next adjacent indentations to thereby index the switch at the proper point in its path of movement for defining an operative or closed circuit position. By moving push button 36 inwardly toward operating handle 30, ball support 26 is moved to the right, as viewed in Fig. 1, while compressing springs 28 to thereby relieve

spring pressure on balls 22 so that they no longer offer any opposition or indexing in response to rotation of actuating shaft 16. The importance of this feature will appear as the description proceeds.

A substantially inverted cup-shaped casing 40 is provided for the switch reset mechanism proper, and this casing may have integral outwardly extending supporting flanges 42 which may be secured to switch casing 4 by the same screws 44 securing cover 6 in place. Mounted within casing 40 on actuating shaft 16 are the various elements of the switch reset mechanism. These include a supporting plate 46 having a circular aperture therein so as to be freely rotatable relative to actuating shaft 16. Supporting plate 46 supports a latch 48, which has a top rearwardly extending lug 50 adapted to be loosely received in a notch 52 provided in extension 64 of supporting plate 46. Latch 48 is also provided with a lower rearwardly extending lug 54 adapted to be loosely received in notch 56 provided in the central opening of supporting plate 46. Lugs 50 and 54 act to loosely mount latch 48 for movement with supporting plate 46 about actuating shaft 16 as an axis. Latch 48 is provided with a pair of side latch arms 58 and 60 which extend outwardly at each side thereof and are bent somewhat towards cover plate 6. Latch 48 is also provided with a pair of spaced forwardly extending release arms 66, 68, having reduced outer ends 66, 92, respectively, and an inclined edge 62 at the under side of arms 66 and 68 adjacent reduced ends 66, 92.

A reset spring 72, in the form of a helical coiled spring is also mounted over actuating shaft 16, and has the ends 74, 76, thereof crossed and extending outwardly in spaced parallel relation to receive therebetween a forwardly extending spring lug 78 also integral with latch 48. As clearly appears from Fig. 2, one end 74 of spring 72 is positioned at one side of spring lug 78, and the other end 76 of the spring is positioned at the other side of spring lug 78.

A second latch supporting member 78 is also mounted on actuating shaft 16, and this support is provided with a substantially D-shaped aperture 80 as to be nonrotatively mounted with respect to the actuating shaft. A second latch 84 is pivotally mounted on support 78, for example, as by a pivot pin 82. Latch 84 is provided with an upwardly and rearwardly extending spring arm 86 also adapted to extend between ends 74 and 76 of spring 72, and support 78 may have the upper end thereof notched to form legs 100 comprising stops for limiting relative pivotal movement of latch 84 by engagement with the reduced rearwardly extending portion of spring arm 86. Latch 84 is provided with a pair of opposed latch arms 88 and 90, and with a second pair of inwardly spaced opposed latch arms 92 and 94, all for a purpose to be described.

Supporting member 78 has a pair of forwardly extending side flanges 102 for receiving therebetween a slidably release plate 104 provided with an aperture 106 for freely receiving actuating shaft 16. A projection 108 is provided in aperture 106 so as to be in alignment with the slot 24 in the actuating shaft and release bar 32 therein. Release plate 104 is provided with a substantially wedge shaped projection 110 in alignment with a V-shaped notch 112 in latch 84, and with rearwardly and upwardly extending release arms 114, 116, all for a purpose to be described.

As previously stated, the outer end of shaft 16 is D-shaped in section. The inner end of shaft

16 is full round in section, and at the point where these two shaft sections meet, a stop shoulder 67 is formed. Stop shoulder 67 prevents movement of support 78 inwardly toward switch cover plate 6.

With the switch in the "off" position shown in Figs. 1 and 3, upon rotation of actuating handle 30 in either direction, spring 72 will be stressed, and the switch will be locked in the position to which it is adjusted against return movement by spring 72. Return of the switch to its "off" position is arranged to be effected by inward movement of push button 36 and release bar 32. In order to explain the operation of the reset mechanism, let us assume that it is desired to rotate actuating shaft 16 in a clockwise direction from the position shown in Figs. 1 and 3 toward the position shown in Fig. 9. Upon the initiating of such movement, latch 84 is also moved in a clockwise direction, because it is mounted on support 78 which is nonrotatable relative to actuating shaft 16. However, spring arm 86 of latch 84 engages spring end 76 and carries it along with it. This tends to cause movement of spring end 74 in the same direction; however as soon as spring end 74 exerts a force on spring lug 70 to the right as viewed in Figs. 2 and 3, latch arm 58 engages cover plate 6. Switch cover plate 6 is provided with a pair of spaced struck-out portions forming shoulders 63 and 65 adjacent latch arms 60 and 58, respectively, in the "off" position of the switch parts. Consequently, as soon as latch arm 58 engages cover plate 6, its movement in a clockwise direction will be halted by shoulder 65.

Accordingly, continued movement of actuating shaft 16 in a clockwise direction will move spring end 76 relative to spring end 74, thus stressing the spring. Since latch 84 is pivotally mounted at 82, spring end 76 engaging spring arm 86 of the latch will cause rotation of the latch about pivot 82 in a counter-clockwise direction and cause latch arm 90 to engage with the inner surface of the side wall of casing 40. This position of latch 84 is shown in Fig. 9 with the switch at a position intermediate its "simmer" and "low" heat positions. As shown in Figs. 1, 3, 4, 5 and 9, the side wall of casing 40 is provided with a plurality of apertures 69 spaced about the casing at points corresponding to the operative positions of the switch. Accordingly, when the switch has been advanced to the desired position, latch arm 90 will engage in the corresponding aperture 69 in casing 40, so that when manual rotating effort is removed, the switch will remain at the position to which it has been adjusted. It is obvious that at such a position of the switch, it may again be manually operated to another position further from the "off" position, or to a position closer to the "off" position or to "off" position itself. If manually operated to "off" position in a counter-clockwise direction, or to another switch position which is toward the "off" position, rotating shaft 16 in a counter-clockwise direction, as viewed in Fig. 9 will cause clockwise rotation of latch 84 about its pivot 82 and latch arm 90 will, accordingly, immediately release from the casing aperture 69 with which it was engaged. However, it is not necessary to manually restore the switch to "off" position by manipulation of handle 30, because this may be easily accomplished by merely depressing push button 36. Assuming that the switch is at a position other than its "off" position and it is desired to utilize the reset mechanism to restore the switch to "off" position, push

button 36 is depressed. This moves release bar 32 to the right, as viewed in Fig. 1, destroying the indexing of balls 22 as previously described, and at the same time cam surface 118 formed as one side of a notch in the edge of the release bar opposite projection 108 on release plate 104, engages projection 108 to move release plate towards latch 84. This causes engagement of wedge shaped projection 110 on the release plate with the sides of V-shaped opening 112 in the latch, to rotate the latch to a position wherein latch arm 90 is withdrawn from the casing aperture 69 with which it has been engaged. Since inward movement of the release bar 32 has destroyed the indexing of balls 22, spring 72 will then be free to restore the actuating shaft to the "off" position of the switch by the action of spring end 76 on latch 84 and support plate 78. The engagement of wedge shaped projection 110 in V-shaped notch 112 of latch 84 prevents rotation of latch 84 about its pivot 82 during resetting movement and thereby prevents either latch arm 88 or 90 from engaging with any apertures 69.

In order to provide for movement of the switch actuating shaft in one direction an amount greater than 360°, and also with a view to decreasing the size and strength requirements of spring 72, there is provided means for locking the two ends of the spring together after actuating shaft 16 has been rotated an amount more than 180° from the "off" position in either direction. In the embodiment of the invention illustrated in the drawings, locking of the two ends of spring 72 occurs after substantially 300° of rotation of actuating shaft 16 in either direction. Assuming rotation of actuating shaft 16 in a clockwise direction 300° from the position shown in Fig. 3 by handle 30, then the parts, assume the position shown in Fig. 4, wherein latch arm 94 of latch 84 engages the reduced end 98 of release arm 68 on latch 48. This not only latches the two ends of the spring together, but also tilts latch 48 in a manner to remove arm 58 from shoulder 65, and also tilts latch 84 about its pivot 82 to remove latch arms 88 and 90 from engagement with the inner side wall of casing 40.

As the position of the part shown in Fig. 4, the switch may be moved by actuating handle 30 to any other desired switch position, including "off" position, or the switch may be automatically reset by depressing push button 36. If it is desired to move the switch by handle 30 to some other position, the only resistance to movement will be that offered by indexing balls 22 and the pressure of bridging contact 10 on contact segments 11 and insulating segments 11. If it is desired to automatically reset the switch with the parts position as shown in Fig. 4, depression of push button 36 will again cause inward movement of release bar 32 and movement of release plate 104 towards latch 84, all as before. However, this time release arm 114 on release plate 104 will engage inclined surface 62 of release arm 68 of latch 48, to tilt latch 48 and release the end 98 of release arm 68 from latch arm 94 of latch 84. Inward movement of release bar 32 destroys the indexing function of balls 22 as previously described. With the ends of spring 72 unlocked, spring end 76 is free to restore actuating shaft 16 to "off" position by its engagement with latch 84. As soon as latch 48 is released from latch arm 94, spring end 74 will cause latch arm 58 on latch 48 to again engage shoulder 65 on cover plate 6 to form a reaction point for this end of the spring. Switch handle 30 may, if desired, be manually

moved to the "off" position from the position shown in Fig. 4. The switch may then be left with spring 72 in the stressed condition shown, or push button 36 may be depressed to unlock the two ends of the spring. In this case, rotation of the shaft is not necessary as the switch is at the "off" position, and as a matter of fact the actuating shaft will not be moved, because, although inward movement of push button 36 destroys the indexing effect of balls 22, rotation of the shaft is still opposed by the friction between bridging contact 18 on the one hand and contact segments 10 and insulating segments 11 mounted on the bottom wall of casing 4 on the other hand. Consequently, when the switch is manually moved to "off" position from the position in Fig. 4, and push button 36 is depressed, latch member 40 will be rotated in a clockwise direction because there is substantially no opposition to movement of this member, since it is mounted on supporting plate 46 and is free to rotate on shaft 16. However, spring end 74 causes the leading latch arm 58 of latch 40 to engage cover plate 6 and this will engage shoulder 65 when the spring is unwound and the two ends are brought together upon opposite sides of spring lug 70 and spring arm 86 at the position of parts shown in Fig. 3.

Instead of manually rotating the switch to "off" position from the position of parts shown in Fig. 4 wherein the two ends of the spring are locked together or instead of automatically resetting the switch by depression of push button 36, it may be desired to move the switch to some other position by means of handle 39. If this is done, the parts may assume a position such as shown in Fig. 5 which is a position substantially 90° from the position shown in Fig. 4. Here again, the switch may be manually manipulated by handle 39 to any other position or to "off" position as described above. Assuming, however, that it is desired to reset the switch to "off" position from the position shown in Fig. 5, depression of push button 36 will destroy the indexing function of balls 22 and cause movement of release plate 104 towards latch 84, as before. This, in turn, will release latch arm 94 from end 98 of release arm 69 so that the spring will then be free to unwind. Since the least resistance is presented to spring end 74, that end will first act to move latch 84 back in a clockwise direction to the position shown in Fig. 3, where it will engage shoulder 65 and be halted. The remaining stress in spring 72 is then forced to be dissipated by spring end 76, and this will cause counterclockwise movement of latch 84, support 78 and actuating shaft 16 in a counterclockwise direction from the position shown in Fig. 5 to the "off" position.

Although, in describing the operation of the switch and spring reset means, it has been assumed that the switch is rotated in a clockwise direction from the "off" position shown in Figs. 1 and 3, it will operate in the same manner if the switch is rotated in a counterclockwise direction from its "off" position. This is due to latches 43 and 84 being formed in an identical manner at opposite sides thereof, so that the only difference in operation upon rotation of the switch in a counterclockwise direction from its "off" position will be that the latch arm 60 will engage shoulder 63 on the cover plate to anchor spring end 76, and latch arm 88 on latch 84 will be biased to engage apertures 69 in the side wall of the cover 40. Latch 84 is released in the same manner by depressing push button 36 to cause projec-

tion 110 on latch release plate 104 to rock latch 84 to a position intermediate its positions wherein latch arms 88 and 98 engage the inner surface of the side wall of casing 40. Release of latch 84 will restore the switch to "off" position in a manner similar to that described above.

From the foregoing it is apparent that this invention comprehends resetting means for switches of the type which are rotatable in either direction from an "off" position any desired amount, which may be actuated by merely pressing a release push button. The reset means is effective to reset the switch to its "off" position even though the switch is manually operated in either direction an unlimited amount. The invention also permits manual return of the switch to "off" position if desired, and in this case if the automatic release is later actuated, the mechanism will restore itself to its normal "off" position without however disturbing the electric circuit condition of the switch. Moreover, these novel functions are obtained by the use of a resetting spring which is maintained at a reasonable strength and size because actuation of the resetting pushbutton destroys some of the resistance to movement of the switch actuating shaft, and also because of the feature of locking the ends of the spring together after predetermined movement, so that additional movement, such as rotation of a plurality of revolutions in the same direction, does not act to further stress the spring.

As previously pointed out, a switch of this type is especially useful in the control of electric ranges where at least 4 such switches are usually provided for the various heating units of the range. It obviously would be a very simple matter to deenergize all the heating units of a range equipped with switches of this type by merely pressing the reset push buttons of the various switches. Furthermore, this positively insures the return of the switch to "off" position and does not require accurate manual adjustment to insure deenergization of the heating units.

Having described a preferred embodiment of the invention in accordance with the patent statutes, it is desired that the invention be not limited to this particular embodiment, inasmuch as it will be obvious, particularly to persons skilled in the art, that many changes and modifications may be made therein without departing from the broad scope of this invention. Accordingly, it is desired that the invention be interpreted as broadly as possible and that it be limited only as required by the prior art.

I claim as my invention:

1. In a switch having a plurality of contacts, contacts actuating means movable in opposite directions from an "off" position in which said contacts are open, to a plurality of spaced operative positions in each of which at least some of said contacts are closed, indexing means operative to frictionally maintain said actuating means at each position thereof, resilient means biasing said actuating means to said "off" position, latch means automatically operable to maintain said actuating means at any of said operative positions to which it is adjusted, and means for simultaneously releasing said latch means and indexing means to permit said resilient means to restore the switch to "off" position.

2. In a switch, a plurality of spaced contacts, cooperating contact means movable in one direction for successively engaging said spaced contacts at successive operative positions, respectively, indexing means defining each of said opera-

tive positions, said indexing means including resiliently biased means engageable with spaced means at said positions, respectively, for increasing the resistance to movement of said movable contact means, and said resiliently biased means arranged to react on said movable contact means to bias the latter into engagement with said contacts at least at each of said positions.

3. In a switch, a plurality of spaced contacts, cooperating contact means movable in one direction from an "off" position for successively engaging said spaced contacts at successive operative positions, respectively, indexing means defining each of said operative positions, said indexing means including resiliently biased means engageable with spaced means at said positions, respectively, for increasing the resistance to movement of said movable contact means, said resiliently biased means arranged to react on said movable contact means to bias the latter into engagement with said contacts at least at each of said position, resilient means biasing said movable contact means to said "off" position, latch means to maintain said movable contact means at each of its operative positions, and means for simultaneously releasing said latch means and the engagement of said resiliently biased means with said spaced means to permit said resilient means to return said movable contact means to "off" position.

4. In a switch having a plurality of contacts, contact actuating means movable in a recurrent path in either direction any amount from an "off" position in which said contacts are open, to a plurality of spaced operative positions in each of which at least some of said contacts are closed, resilient means biasing said actuating means to its "off" position from any of said operative positions, latch means automatically operative at said operative positions to prevent return of said actuating means by said resilient means, and means for releasing said latch means.

5. In a switch having a plurality of contacts, contact actuating means rotatable any amount in either direction from an "off" position in which said contacts are open, to a plurality of spaced operative positions in each of which at least some of said contacts are closed, resilient means biasing said actuating means to its "off" position from any of said operative positions, latch means automatically operative at said operative positions to prevent return of said actuating means by said resilient means, and means for releasing said latch means.

6. In a switch having a plurality of contacts, contact actuating means rotatable any amount in either direction from an "off" position in which said contacts are open, to a plurality of spaced operative positions in each of which at least some of said contacts are closed, means for returning said actuating means to "off" position including a latch member movable with said actuating means and another latch member movable relative to said actuating means, stationary latch portions positioned to cooperate with said other latch member substantially at "off" position for preventing movement thereof in either direction, annularly arranged spaced latch portions positioned to cooperate with said one latch member at said operative positions, respectively, resilient means engaging said latch members so as to be stressed by relative movement thereof, means responsive to movement of said actuating means in either direction from "off" position to

cause latching of said other latch member with one of its stationary latch portions and positioning of said one latch member for engagement with said annularly arranged latch portions to latch said actuating means at the operative position to which it is adjusted with said resilient means stressed an amount sufficient to return said actuating means to "off" position, and means for moving said one latch member to a position at which it is out of engagement with said annularly arranged latch portions thereby permitting said resilient means to reset said switch to "off" position.

7. In a switch having a plurality of contacts, contact actuating means rotatable any amount in either direction from an "off" position in which said contacts are open to a plurality of spaced operative positions in each of which at least some of said contacts are closed, means for returning said actuating means to "off" position including a latch member movable with said actuating means, annularly arranged spaced latch portions positioned to cooperate with said latch member at said operative positions, respectively, resilient means engaging said latch member so as to be stressed upon movement thereof in either direction from "off" position, means responsive to movement of said actuating means in either direction from "off" position to position said latch member for engagement with said annularly arranged latch portions to latch said actuating means at the operative position to which it is adjusted with said resilient means stressed an amount sufficient to return said actuating means to "off" position, and means for moving said latch member to a position at which it is out of engagement with said annularly arranged latch portions thereby permitting said resilient means to reset said switch to "off" position.

8. In a switch having a plurality of contacts, contact actuating means rotatable any amount in either direction from an "off" position in which said contacts are open to a plurality of spaced operative positions in each of which at least some of said contacts are closed, means for returning said actuating means to "off" position including a latch member movable with said actuating means and another latch member movable relative to said actuating means, stationary latch portions positioned to cooperate with said other latch member substantially at "off" position for preventing movement thereof in either direction, annularly arranged spaced latch portions positioned to cooperate with said one latch member at said operative positions, respectively, resilient means engaging said latch members so as to be stressed by relative movement thereof, means responsive to movement of said actuating means in either direction from "off" position to cause latching of said other latch member with one of its stationary latch portions and positioning of said one latch member for engagement with said annularly arranged latch portions to latch said actuating means at the operative position to which it is adjusted with said resilient means stressed an amount sufficient to return said actuating means to "off" position, means responsive to at least 180° of movement of said actuating means from said "off" position to latch said latch members together and move said members to disengaged position relative to their cooperating latch portions, and means for releasing said latch members to permit said spring to reset the switch.

9. In a switch having a plurality of contacts,

contact actuating means rotatable any amount in either direction from an "off" position in which said contacts are open to a plurality of spaced operative positions in each of which at least some of said contacts are closed, means for returning said actuating means to "off" position including a latch member movable with said actuating means and another latch member movable relative to said actuating means, stationary latch portions positioned to cooperate with said other latch member substantially at "off" position for preventing movement thereof in either direction, annularly arranged spaced latch portions positioned to cooperate with said one latch member at said operative positions, respectively, resilient means engaging said latch members so as to be stressed by relative movement thereof, means responsive to movement of said actuating means in either direction from "off" position to cause latching of said other latch member with one of its stationary latch portions and positioning of said one latch member for engagement with said annularly arranged latch portions to latch said actuating means at the operative position to which it is adjusted with said resilient means stressed an amount sufficient to return said actuating means to "off" position, means responsive to at least 180° of movement of said actuating means to latch said latch members together and move said members to disengaged positions relative to their cooperating latch portions, and means acting on said one latch member to release the other latch member and maintain said one latch member at a position at which it is out of engagement with said annularly arranged latch portions thereby permitting said resilient means to reset said switch to "off" position.

10. In a switch having a plurality of contacts, contact actuating means rotatable any amount in either direction from an "off" position in which said contacts are open to a plurality of spaced operative positions in each of which at least some of said contacts are closed, means for returning said actuating means to "off" position including a latch member movable with said actuating means and another latch member movable relative to said actuating means, stationary latch portions positioned to cooperate with said other latch member substantially at "off" position for preventing movement thereof in either direction, annularly arranged spaced latch portions positioned to cooperate with said one latch member at said operative positions, respectively, resilient means engaging said latch members so as to be stressed by relative movement thereof, means responsive to movement of said actuating means in either direction from "off" position to cause latching of said other latch member with one of its stationary latch portions, means responsive to tensioning of said resilient means to position said one latch member for engagement with said annularly arranged latch portions to latch said actuating means at the operative position to which it is adjusted with said resilient means stressed an amount sufficient to return said actuating means to "off" position, and means for moving said one latch member to a position at which it is out of engagement with said annularly arranged latch portions thereby permitting said resilient means to reset said switch to "off" position.

11. In a switch having a plurality of contacts, contact actuating means rotatable any amount in either direction from an "off" position in which said contacts are open, to a plurality of spaced op-

erative positions in each of which at least some of said contacts are closed, means for returning said actuating means to "off" position including resilient means a portion of which is movable with said actuating means, means holding another portion of said resilient means substantially fixed for at least 180° of rotation of said actuating means from "off" position, means for thereafter locking said two portions of said resilient means together with said resilient means in stressed condition, means for releasing said portions for retrograde movement, and means preventing retrograde movement of said other portion of said resilient means beyond said "off" position, whereby said one portion of said resilient means is effective to restore said actuating means to "off" position.

12. In a switch having a plurality of contacts, contact actuating means rotatable any amount in either direction from an "off" position in which said contacts are open, to a plurality of spaced operative positions in each of which at least some of said contacts are closed, means for returning said actuating means to "off" position including resilient means a portion of which is movable with said actuating means, means holding another portion of said resilient means substantially fixed for at least 180° of rotation of said actuating means from "off" position, means for thereafter locking said two portions of said resilient means together with said resilient means in stressed condition, means for latching said actuating means against retrograde movement at least at each operative position up to said 180° of rotation, means for releasing said latching means and said portions for retrograde movement, and means preventing retrograde movement of said other portion of said resilient means beyond said "off" position, whereby said one portion of said resilient means is effective to restore said actuating means to "off" position.

13. In a switch having a plurality of contacts, contact actuating means movable in a recurrent path in either direction any amount from an "off" position in which said contacts are open, to a plurality of spaced operative portions in each of which at least some of said contacts are closed, indexing means defining each of said operative positions by a change in the resistance to movement of said actuating means, resilient means biasing said actuating means to its "off" position from any of said operative positions, latch means automatically operative at said operative positions to prevent return of said actuating means by said resilient means, and means for concurrently rendering said indexing means ineffective and releasing said latch means.

14. In a switch having a plurality of contacts, contact actuating means rotatable any amount in either direction from an "off" position in which said contacts are open, to a plurality of spaced operative positions in each of which at least some of said contacts are closed, means for returning said actuating means to "off" position including a latch member movable with said actuating means and another latch member movable relative to said actuating means, stationary latch portions positioned to cooperate with said other latch member substantially at "off" position for preventing movement thereof in either direction, annularly arranged spaced latch portions positioned to cooperate with said one latch member at said operative positions, respectively, resilient means engaging said latch members so as to be stressed by relative movement thereof, means re-

sponsive to movement of said actuating means in either direction from "off" position to cause latching of said other latch member with one of its stationary latch portions and positioning of said one latch member for engagement with said annularly arranged latch portions to latch said actuating means at the operative position to which it is adjusted with said resilient means stressed an amount sufficient to return said actuating means to "off" position, indexing means defining each of said operative positions by a change in the resistance to movement of said actuating means, and means for concurrently rendering said indexing means ineffective and moving said one latch member to a position at which it is out of engagement with said annularly arranged latch portions thereby permitting said resilient means to reset said switch to "off" position.

15. In a switch having a plurality of contacts, contact actuating means rotatable any amount in either direction from an "off" position in which said contacts are open to a plurality of spaced operative positions in each of which at least some of said contacts are closed, means for returning said actuating means to "off" position including a latch member movable with said actuating means, annularly arranged spaced latch portions positioned to cooperate with said latch member at said operative positions, respectively, resilient means engaging said latch member so as to be stressed upon movement thereof in either direction from "off" position, means responsive to movement of said actuating means in either direction from "off" position to position said latch member for engagement with said annularly arranged latch portions to latch said actuating means at the operative position to which it is adjusted with said resilient means stressed an amount sufficient to return said actuating means to "off" position, indexing means defining each of said operative positions by a change in the resistance to movement of said actuating means, and means for concurrently rendering said indexing means ineffective and moving said latch member to a position at which it is out of engagement with said annularly arranged latch portions thereby permitting said resilient means to reset said switch to "off" position.

16. In a switch having a plurality of contacts, contact actuating means rotatable any amount in either direction from an "off" position in which said contacts are open, to a plurality of spaced operative positions in each of which at least some of said contacts are closed, means for returning said actuating means to "off" position including a latch member movable with said actuating means and another latch member movable relative to said actuating means, stationary latch portions positioned to cooperate with said other latch member substantially at "off" position for preventing movement thereof in either direction, annularly arranged spaced latch portions positioned to cooperate with said one latch member at said operative positions, respectively, resilient means engaging said latch members so as to be stressed by relative movement thereof, means responsive to movement of said actuating means in either direction from "off" position to cause latching of said other latch member with one of its stationary latch portions and positioning of said one latch member for engagement with said annularly arranged latch portions to latch said actuating means at the operative position to which it is adjusted with said resilient means stressed an amount sufficient to return said actuating means

to "off" position, indexing means defining each of said operative positions by a change in the resistance to movement of said actuating means, means responsive to at least 180° of movement of said actuating means to latch said latch members together and move said members to disengaged positions relative to their cooperating latch portions, and means for concurrently rendering said indexing means ineffective and releasing said latch members to permit said spring to reset the switch.

17. In a switch having a plurality of relatively movable contacts, a rotatable contact actuating shaft movable from an "off" position in which said contacts are disengaged to a plurality of operative positions in each of which certain of said contacts are engaged, resilient means biasing said shaft to said "off" position from each of said operative positions, latch means for automatically maintaining said shaft at each operative position, and means movable longitudinally of said shaft substantially along the axis thereof for releasing said latch means to permit said spring to return said shaft to "off" position.

18. In a switch having a plurality of contacts, contact actuating means rotatable any amount in either direction from an "off" position in which said contacts are open to a plurality of spaced operative positions in each of which at least some of said contacts are closed, resilient means biasing said actuating means to its "off" position from any of said operative positions, latch means automatically operative at said operative positions to prevent return of said actuating means by said resilient means, and means movable longitudinally of the axis of rotation of said actuating means and substantially along said axis for releasing said latch means.

19. In a switch having a plurality of relatively movable contacts, a rotatable contact actuating shaft movable from an "off" position in which said contacts are disengaged to a plurality of operative positions in each of which certain of said contacts are engaged, resilient means biasing said shaft to said "off" position from each of said operative positions, latch means for automatically maintaining said shaft at each operative position, said shaft having a longitudinal passage, and means slidably through said passage for releasing said latch means to permit said spring to return said shaft to "off" position.

20. In a switch having a plurality of relatively movable contacts, a rotatable contact actuating shaft movable from an "off" position in which said contacts are disengaged to a plurality of operative positions in each of which certain of said contacts are engaged, resilient means biasing said shaft to said "off" position, latch means for automatically maintaining said shaft at an operative position, said shaft having a longitudinal passage, means slidably through said passage for releasing said latch means to permit said spring to return said shaft to "off" position, an actuating handle having an aperture for drivingly receiving said shaft, and a push button on said slidable means outwardly of said handle.

21. In a switch, a rotatable switch actuating shaft, a plurality of spaced contacts arranged about said shaft, movable contact means slidably but non-rotatably carried by said shaft for successively engaging said spaced contacts upon rotation of said shaft in one direction, indexing means for said switch including a member arranged about said shaft and a cooperating member associated with said movable contact

means, one of said members having annularly arranged depressions and the other of said members including projection means adapted to be received in a depression at each position of said switch, resilient means biasing one of said members toward the other with said bias exerted generally longitudinally of said shaft so the reaction thereof also biases said movable contact means towards said spaced contacts.

22. In a switch, a rotatable switch actuating shaft, a plurality of spaced contacts arranged about said shaft, movable contact means slidably but non-rotatably carried by said shaft for successively engaging said spaced contacts upon rotation of said shaft in one direction, indexing means for said switch including a member arranged about said shaft and a cooperating member associated with said movable contact means, one of said members having annularly arranged depressions and the other of said members including projection means adapted to be received in a depression at each position of said switch, resilient means biasing one of said members toward the other with said bias exerted generally longitudinally of said shaft so the reaction thereof also biases said movable contact means towards said spaced contacts and manually operable means for relieving at least one of said members of said resilient bias to destroy indexing.

23. In a switch, a rotatable switch actuating shaft, a plurality of spaced contacts arranged about said shaft, movable contact means slidably but non-rotatably carried by said shaft for successively engaging said spaced contacts upon rotation of said shaft in one direction, indexing means for said switch including a member arranged about said shaft and a cooperating member associated with said movable contact means, one of said members having annularly arranged depressions and the other of said members including projection means adapted to be received in a depression at each position of said shaft wherein said movable contact means engages a spaced contact and at an "off" position, resilient means biasing one of said members toward the other with said bias exerted generally longitudinally of said shaft so the reaction thereof also biases said movable contact means towards said spaced contacts, second resilient means biasing said shaft to "off" position, latch means for automatically maintaining said switch at a closed circuit position to which it is adjusted, manually operable means movable longitudinally of said shaft for relieving at least one of said members of said resilient bias to destroy indexing, and said manually operable means having a cam surface for concurrently releasing said latch means to permit said second resilient means to restore the switch to its "off" position.

24. In a switch having a plurality of relatively movable contacts, a rotatable contact actuating shaft movable from an "off" position in which said contacts are disengaged to a plurality of operative positions in each of which certain of said contacts are engaged, resilient means for returning said shaft when at each of said operative positions to said "off" position, latch means for automatically maintaining said shaft at each operative position, an actuating handle having an aperture for drivingly receiving said shaft, and a push button slidably mounted on said shaft outwardly of said handle for releasing said latch

means to permit said resilient means to return said shaft to "off" position.

25. In a switch having a plurality of contacts, contact actuating means rotatable any amount in either direction from an "off" position in which said contacts are open, to a plurality of spaced operative positions in each of which at least some of said contacts are closed, means for returning said actuating means to "off" position including resilient means a portion of which is movable with said actuating means, means holding another portion of said resilient means substantially fixed for at least 180° of rotation of said actuating means from "off" position, means for thereafter locking said two portions of said resilient means together with said resilient means in stressed condition, means for latching said actuating means against retrograde movement at least at each operative position up to said 180° of rotation, means for releasing said latching means and said portions for retrograde movement, means preventing retrograde movement of said other portion of said resilient means beyond said "off" position, whereby said one portion of said resilient means is effective to restore said actuating means to "off" position, and indexing means defining at least the operative positions beyond said 180° of rotation by a change in the resistance to movement of said actuating means.

26. In a switch having a plurality of contacts, contact actuating means rotatable any amount in either direction from an "off" position in which said contacts are open, to a plurality of spaced operative positions in each of which at least some of said contacts are closed, means for returning said actuating means to "off" position including resilient means a portion of which is movable with said actuating means, means holding another portion of said resilient means substantially fixed for at least 180° of rotation of said actuating means from "off" position, means for thereafter locking said two portions of said resilient means together with said resilient means in stressed condition, means for latching said actuating means against retrograde movement at least at each operative position up to said 180° of rotation, indexing means defining at least the operative positions beyond said 180° of rotation by a change in the resistance to movement of said actuating means, means for concurrently releasing said indexing means, said latching means and said portions for retrograde movement, and means preventing retrograde movement of said other portion of said resilient means beyond said "off" position, whereby said one portion of said resilient means is effective to restore said actuating means to "off" position.

27. In a switch having a plurality of contacts, contact actuating means movable in a recurrent path in either direction any amount from an "off" position in which said contacts are open, to a plurality of spaced operative positions in each of which at least some of said contacts are closed, resilient means adapted to be stressed in response to movement of said actuating means from said "off" position to any of said operative positions for returning said actuating means to said "off" position, latch means automatically operative at said operative positions to prevent return of said actuating means by said resilient means, and means for releasing said latch means.

JAMES F. BEAL.
